COLLAPSIBLE CELLULAR CARTON

William H. Inman, Newark, N. Y., assignor to Bloomer Bros. Company, Newark, N. Y., a corporation of New York

Application January 5, 1953, Serial No. 329,622

7 Claims. (Cl. 229—28)

This invention relates to cellular cartons of the variety made from cardboard or other suitable sheet material, for containing eggs or other fragile articles, one object of the invention being to provide an improved carton of the above character having a more simple, practical and efficient construction affording a high degree of strength and resistance to crushing, particularly under vertical pressure on the carton or the contents thereof.

Another object is to provide a carton having the above advantages which is capable of being readily cut from sheet material, scored for folding, folded and glued in collapsed condition, and of being easily swung to erected condition by automatic machines of known construction.

A further object is to provide a carton of the above character having a form of construction which eliminates externally projecting supporting legs or other irregular projections and presents smooth outer wall surfaces when in erected condition so as to obviate entanglement with one another and to facilitate the stacking of quantities of filled cartons.

Still a further object is to provide a carton having the above advantages which requires a minimum amount of material in proportion to its strength and which is capable of being readily and economically manufactured.

To these and other ends the invention resides in certain improvements and combinations of parts, all as will be hereinafter more fully described, the novel features being pointed out in the claims at the end of the specification.

In the drawings:

Fig. 1 is a plan view of a blank of sheet material cut, scored and glued in accordance with my invention, preparatory to folding;

Fig. 2 is an enlarged fragmentary plan view of the top wall of the carton as shown in Fig. 1;

Fig. 3 is an end elevation showing the completed carton in the process of erection;

Fig. 4 is an enlarged end elevation of the erected carton, and

Fig. 5 is a perspective view showing the carton in erected condition.

This invention is an improvement on the general type of carton disclosed in my prior Patent No. 2,556,088, for the purpose of producing a stronger and more practical, economical and convenient carton.

The embodiment of the present invention, herein disclosed by way of illustration, preferably comprises a one-piece blank, shown generally at 21, of cardboard or other suitable sheet material, cut, scored and glued for folding, as shown in Fig. 1. The blank is shown in Fig. 1 with the outer surfaces of the carton uppermost in order to more clearly show the various cut and score lines which form the parts of the carton, hereinafter described. The blank is of generally rectangular shape adapted to be economically cut from stock material, and comprises in order, as shown in Fig. 1, a locking flap 23, cover 25, rear wall 27, outer bottom wall 29,

2

lower longitudinal partition member 31, inner bottom plies 33 and 35, upper longitudinal partition members 37 and 39, inner bottom plies 41 and 43, lower longitudinal partition member 45, outer bottom wall 47, a front wall 49, a top wall 51, and an attaching strip 53.

The above sections of the blank are separated by score lines extending across the blank, as shown by multiple lining in the drawings, to facilitate folding, as well understood in the art. The top wall 51 is cut and scored for the downfolding of a series of cross partitions having three different configurations, as shown at 55, 57 and 59 (Fig. 1), for separating the carton longitudinally into cells.

Thus, the blank is cut through along lines 61 and scored along the lines 63 to permit the down folding of the cross partitions as shown in Fig. 5, for coaction with a central longitudinal partition, hereinafter described, to divide the carton into a dozen article-receiving cells. The top wall has a series of short, transversely-extending score lines 65 (Fig. 2), located adjacent opposite sides thereof, which in conjunction with score lines 63 form a series of substantially triangular hinge portions 67 about which the transverse partitions may be swung to their down-folded positions, as shown in Fig. 5. Score lines 63 and 65 preferably have short cuts or slits 69 (Fig. 2) formed therein for decreasing the resistance to folding of the carton parts along said score lines.

The lower edges of the transverse partitions are preferably notched or slotted centrally, as at 71 (Fig. 2) for engagement with the longitudinal partition. The transverse partitions are each preferably provided with a pair of short cuts or slits 73 (Fig. 2) which in conjunction with the central slit 71 in each partition form a pair of tabs adapted to yield slightly as the transverse partitions

are swung into engagement with the longitudinal partition to assist in the frictional engagement between the transverse partitions and the longitudinal partition, as disclosed in my prior Patents Nos. 2,277,327 and 2,556,088. The upper edges of partitions 57 and 59 are preferably notched or slotted centrally, as at 76 (Fig. 2), for allowing the upper portions of the longitudinal partition to extend upwardly through the top wall when the carton is in collapsed condition as can be seen from inspection of the carton in partially collapsed condition shown in

Fig. 3. Each cross partition is centrally scored longitudinally of the carton, as at 75 (Fig. 2), in addition to slits 71 therein and slits 76 in partitions 57 and 59, to facilitate the central folding of the transverse partitions and top wall in the collapsed condition of the carton, as hereinafter more fully described. The partitions are preferably so arranged that, when the blank is turned over and folded, the three partitions adjacent the right end of the blank, as viewed in Fig. 1, fold downwardly in a clockwise direction to their erected positions shown in Fig. 5, while the remaining four partitions are arranged to swing in a counterclockwise direction to their erected positions shown in Fig. 5.

The longitudinal partition members 37 and 39 which form the upper section of the partition are formed with cut-out portions or notches, as a 77 (Fig. 1) to provide, when erected, a series of notches in the upper portions of the longitudinal partition. Notches 77 are open at the upper ends thereof and are arranged to receive the transverse partitions which swing down and engage the lower portion of the longitudinal partition in the slits 71 thereof. Partition members 37 and 39 are separated by an interrupted score or fold line 79 (Fig. 1) extending longitudinally of the carton to assist in reversely folding the partition members to their juxtaposed positions shown in Figs. 4 and 5. Members 37 and 39 are separated from the adjacent upper plies 35 and 41, respectively, of the inner

cushioning bottom sections by longitudinally extending score lines 81 and 83.

Upper ply 35 is separated from the adjacent lower ply 33 of the inner bottom by a longitudinally-extending score line 85 (Fig. 1). Upper ply 41 is similarly separated from lower ply 43 by a score line 87. Upper and lower plies 33 and 35 are preferably provided with a band or strip of glue or other suitable adhesive, as at 89 for securing the same together, when reversely folded along fold line 85, for forming a double thickness inner cushioning bottom section shown generally at 91 (Fig. 4). Plies 41 and 43 are similarly provided with glue or other suitable adhesive, as at 93 (Fig. 1), for securing the same together, when they are reversely folded about fold line 87, for forming a second double thickness inner cushioning bottom section, shown generally at 95 (Fig. 4).

Lower ply 33 is separated from longitudinal partition lower member 31 by a score line 97 (Fig. 1). Lower ply 43 is similarly separated from longitudinal partition lower member 45 by a score line 99 (Fig. 1). Partition members 31 and 45 are preferably provided with glue or other suitable adhesive as at 101 (Fig. 1) for securing the same together in juxtaposed relationship for forming the lower section or portion of the longitudinal partition, shown generally at 103 (Fig. 4), when the carton is folded and glued.

Outer bottom wall 29 is separated from longitudinal member 31 by a score line 105 and from rear wall 27 by a score line 107, as shown in Fig. 1. Outer bottom wall 47 is separated from longitudinal partition member 45 by a score line 109 and from front wall 49 by a score line 111 (Fig. 1). Cover 25 is separated from rear wall 27 by a score line 113 and from closure flap 23 by a score line 115 (Fig. 1). Front wall 49 is separated from top wall 51 by an irregular, longitudinally extending fold line formed in part by the series of spaced cuts 61 and in part by the series of spaced score lines 63. Attaching strip 53 is similarly separated from the opposite side of the top wall by the respective series of spaced cuts 61 and score lines 63.

The folding and gluing of the carton is preferably done as follows: The blank is passed through a gluing machine which applies glue or other suitable adhesive at 89, 93, 101 and along the upper surface, as viewed in Fig. 1, of attaching strip 53, as at 117. The longitudinal partition members 37 and 39 are reversely folded along the fold line 79, inner bottom plies 33 and 35 reversely folded along fold line 85 and adhesively secured together for forming inner bottom section 91, and inner bottom plies 41 and 43 are reversely folded along fold line 87 and glued together for forming inner bottom section 95. Thereafter longitudinal partition members 31 and 35 are brought into juxtaposed position and adhesively secured together thereby forming the lower section 103 of the longitudinal partition. Outer bottom walls 29 and 47 are folded outwardly about lines 105 and 109, respectively. Front wall 49 and top wall 51 are then folded as a unit about outer bottom wall 47 along score line 111, bringing the top wall into engagement with the upper portion of the longitudinal partition. Top wall 51 is then reversely folded about score line 75, thereby swinging the rearward portions of the top wall and attaching strip 53 downwardly over the longitudinal partition so that when the carton is collapsed to substantially flat condition and rear wall 27 folded relative to bottom wall 29 along score line 107, attaching strip 53 is brought into engagement with the inner surface of the back wall and is secured thereto by the strip of adhesive 117.

The carton is thus in substantially the condition shown in Fig. 3, but is more tightly-collapsed and is ready for storage or shipment to the purchaser in compact, flat condition. The carton may thereafter be readily swung to its erected position shown in Figs. 4 and 5 in the following manner. The transverse partitions are first forced

downwardly into the notches 77 in the longitudinal partition while said longitudinal partition is forced downwardly to move outer bottom walls 29 and 47 into nearly coplanar relationship and spread the front and rear walls, as shown in Fig. 4. At this point the transverse partitions are substantially horizontal and may be readily swung to their substantially vertical erected positions by hand, or by known erecting devices, thereby completing the erection of the carton. Partitions 55 and 57 are preferably shaped so that the lower edges thereof engage the upper surfaces of inner bottom plies 35 and 41 for holding inner bottom sections 91 and 95, respectively, in their inclined positions, shown in Fig. 4, and for increasing the frictional interengagement of the carton parts in the erected condition thereof.

After filling, cover 25 is folded along score line 113, locking flap 23 folded along score line 115 into depending relation relative to cover 25. Flap 23 is provided with a series of locking hooks 119 and a tab 121 which are moved downwardly into engagement with and between hinge portions 67 for securing the cover in closed position, as well understood in the art.

Transverse partitions 55 and 57 are preferably so shaped that when in their erected positions, as shown in Figs. 4 and 5, the upper edges thereof are of sufficient height so as to engage and support the center of cover 25 as said cover is swung about fold line 113 to its closed position, shown in broken lines in Fig. 4. In addition, the longitudinal partition is preferably of substantially the same height as the above transverse partitions so that it also is in supporting engagement with the cover, as shown in Fig. 4. As a result of this construction the carton is able to withstand heavy shocks and crushing forces without damage to the contents of the carton. That is, vertical loads on the cover are transmitted directly to the outer bottom of the carton by the longitudinal partition or through the transverse partitions and inner cushioning bottom sections to the outer bottom of the carton. Lower longitudinal partition section 103, inner bottom sections 91 and 95 and outer bottom walls 29 and 47 form a truss-like construction of substantially triangular shape, comprising in effect two smaller, truss-like triangles, which imparts considerable strength to the upper portion of the longitudinal partition, the transverse partitions, and through the transverse and longitudinal partitions to the cover. As a result of my improved construction, cartons of the above type may be conveniently stacked one upon another without fear of crushing the contents and, as there are no depending feet, the outer surfaces of the carton are smooth and are not likely to engage or entangle one another.

Transverse partitions 55 are provided on opposite sides thereof with small projecting lugs 123 (Fig. 2) which are adapted to engage the inner surfaces of the front and rear walls when the partitions are swung to erected position, as shown in Fig. 4, thereby increasing the frictional engagement between partitions 55 and the side walls of the carton. Partitions 57 have similar lugs or projections 125 formed therein, and are provided with a pair of short slits or cuts 127 which increase the flexibility of said lugs and allow the same to bend out of alignment with the main portion of partitions 57 so as to provide an enlarged area of frictional engagement between the partitions and the front and rear walls of the carton. Each of the transverse partitions is also provided with the pair of spaced upwardly tapered slits or cuts 73 which, in conjunction with central slit 71, form a pair of substantially triangular tab portions which are adapted to bend as the transverse partitions are swung into erected position. These tab portions allow the transverse partitions to straddle the double-thickness longitudinal partition and serve to increase the frictional engagement therebetween so as to more securely hold the transverse partitions in their erected positions and thereby hold the carton in erected position. In addition, partitions 55 are preferably pro-

vided with a series of interrupted cut or slit lines 129 arranged as shown in Figs. 1 and 2 for allowing partitions 55 to bow outwardly towards the adjacent end of the carton between the front wall and the longitudinal partition, and between the longitudinal partition and the rear wall, thereby increasing the length of the end cells of the carton.

The parts are preferably so constructed that the longitudinal partition is of greater height than the top wall of the carton when the carton is in its collapsed position, as can be seen from inspection of Fig. 3, in which the carton is in partially collapsed condition. That is, the upper ends of the longitudinal partition extend upwardly through slits 71 in the transverse partitions so that, upon completion of the folding and gluing of the carton, the parts are in proper alignment and there is no need for special handling operations or special apparatus to insure the proper alignment of the parts during the erection thereof.

Thus, it will be seen that my invention provides an improved carton having inner cushioning bottom sections which support and cradle the contents of the carton and yet which are spaced from the outer bottom of the carton so that shocks or impacts will be absorbed by or transmitted through the carton without injury to the contents thereof. As the inner cushioning bottom sections may yield or bow downwardly and, because of the resiliency of the cardboard, they form an effective resilient support for the contents. The cover of the carton is not only supported along the rear edge thereof by rear wall 27 and along the front edge thereof by front wall 49 and closure flap 23, but it is also supported between the front and rear edges thereof by the upper edges of the transverse partitions and the upper edge of the longitudinal partition, thereby greatly increasing the resistance of the carton to vertical forces or impacts. My improved carton has the further advantages that the above construction is accomplished with a minimum of material, and the carton is of such a type that it may be readily and economically manufactured and folded to collapsed condition for shipment or storage. Thereafter, the carton may be readily erected by hand or by mechanical erecting devices to its condition shown in Figs. 4 and 5, since the top wall and longitudinal partition are continuously engaged and guided in movement upon each other.

It will thus be seen that the invention accomplishes its objects and, while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A cellular carton comprising a blank of sheet material cut, scored and folded to form front and rear side walls, a double thickness central longitudinal partition having upper and lower sections, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and the respective outer bottom walls, said inner bottom sections having upper plies connected to the respective lower plies along the outer edges thereof and extending upwardly and inwardly towards the center of the carton.

towards the center of the carton, a second pair of upwardly extending longitudinal partition members hingedly connected to the respective upper plies of the inner cushioning bottom sections adjacent the upper edges thereof for forming the upper section of said longitudinal partition, said second pair of partition members being hingedly connected to each other along the upper edges thereof, and a top wall hinged to and connected with said front and rear walls and having therein a series of transverse partitions hingedly connected thereto and folded downwardly therefrom between said side walls and on opposite sides of said longitudinal partition to provide a plurality of cushioned article-receiving cells.

2. A cellular carton comprising a blank of sheet material cut, scored and folded to form front and rear side walls, a double thickness central longitudinal partition having upper and lower sections, a cover hinged to said rear wall, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and the respective outer bottom walls, said inner bottom sections having upper plies connected to the respective lower plies along the outer edges thereof and extending upwardly and inwardly towards the center of the carton, a second pair of upwardly extending longitudinal partition members hingedly connected to the respective upper plies of the inner cushioning bottom sections along the upper edges thereof for forming the upper section of said longitudinal partition, said second pair of partition members having their upper edges hingedly connected together and located in supporting proximity to said cover, and a top wall hinged to and connected with said front and rear walls and having therein a series of transverse partitions hingedly connected thereto and folded downwardly therefrom between said side walls and on opposite sides of said longitudinal partition to provide a plurality of cushioned article-receiving cells.

3. A cellular carton comprising a blank of sheet material cut, scored and folded to form front and rear side walls, a double thickness central longitudinal partition having upper and lower sections, a cover hinged to said rear wall, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and the respective outer bottom walls, said inner bottom sections having upper plies connected to the respective lower plies along the outer edges thereof and extending upwardly and inwardly towards the center of the carton in overlying relation with said respective lower plies, a second pair of upwardly extending longitudinal partition members hingedly connected to the respective upper plies of the inner cushioning bottom sections adjacent the upper edges thereof for forming the upper section of said longitudinal partition, said second pair of partition members being hingedly connected to each other along the upper edges thereof, and a top wall hinged to and connected with said front and rear walls and having therein

a series of transverse partitions hingedly connected thereto and folded downwardly therefrom between said side walls and on opposite sides of said longitudinal partition to provide a plurality of cushioned article-receiving cells, said transverse partitions having their upper edges located in supporting proximity to said cover when the partitions are in said down folded position.

4. A cellular carton comprising a blank of sheet material cut, scored and folded to form front and rear side walls, a double thickness central longitudinal partition having upper and lower sections, a pair of outer bottom walls hingedly connected to said side walls along the lower edges thereof and extending inwardly into proximity with each other, a pair of longitudinally extending members hingedly connected along the lower edges thereof to the respective outer bottom walls and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and the respective outer bottom walls, said inner bottom sections having upper plies connected to the respective lower plies along the outer edges thereof and extending upwardly and inwardly towards the center of the carton, a second pair of upwardly extending longitudinal partition members hingedly connected to the respective upper plies of the inner cushioning bottom sections adjacent the upper edges thereof for forming the upper section of said longitudinal partition, said second pair of partition members being hingedly connected to each other along the upper edges thereof, and a top wall hinged to said front wall adjacent the upper edge thereof and being foldably connected with said rear wall, said top wall having therein a series of transverse partitions hingedly connected thereto and folded downwardly therefrom between said side walls and on opposite sides of said longitudinal partition to provide a plurality of cushioned article-receiving cells, said top wall also being formed with a central longitudinal score line, whereby said top wall and transverse partitions may be folded upwardly in continuous engagement with said longitudinal partition while said outer bottom walls are foldable downwardly about the hinge connections between said outer bottom walls and the respective longitudinal partition members for collapsing said carton to substantially flat condition.

5. A cellular carton comprising a blank of sheet material cut, scored and folded to form front and rear side walls, a double thickness central longitudinal partition having upper and lower sections, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and the respective outer bottom walls, said inner bottom sections having upper plies connected to the respective lower plies along the outer edges thereof and extending upwardly and inwardly towards the center of the carton, a second pair of upwardly extending longitudinal partition members hingedly connected to the respective upper plies of the inner cushioning bottom sections adjacent the upper edges thereof for forming the upper section of said longitudinal partition, said second pair of partition members being hingedly connected to each other along the upper edges thereof, and a top wall hinged to and connected with said front and rear walls and hav-

ing therein a series of transverse partitions hingedly connected thereto and folded downwardly therefrom between said side walls and on opposite sides of said longitudinal partition to provide a plurality of cushioned article-receiving cells, said inner cushioning bottom sections engaging said outer bottom walls adjacent the outer edges thereof and being held in spaced relationship therewith along the inner edges of the longitudinal partition; said inner cushioning bottom sections, outer bottom walls and lower section of the longitudinal partition forming a relatively rigid, truss-like support of substantially triangular shape for firmly supporting said inner cushioning bottom sections and longitudinal partition, with a smooth outer bottom surface for said carton.

6. A cellular carton comprising a blank of sheet material cut, scored and folded to form front and rear side walls, a double thickness central longitudinal partition having upper and lower sections, a cover hinged to said rear wall, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner cushioning bottom sections having lower plies hingedly connected to said upwardly extending members along the upper edges thereof and extending downwardly and outwardly into proximity with the junction between said side walls and the respective outer bottom walls, said inner bottom sections having outer plies connected to the respective lower plies along the outer edges thereof and extending upwardly and inwardly towards the center of the carton, a second pair of upwardly extending longitudinal partition members hingedly connected to the respective upper plies of the inner cushioning bottom sections along the upper edges thereof for forming the upper section of said longitudinal partition, said second pair of partition members having their upper edges hingedly connected together and located in supporting proximity to said cover, and a top wall hinged to and connected with said front and rear walls and having therein a series of transverse partitions hingedly connected thereto and folded downwardly therefrom between said side walls and on opposite sides of said longitudinal partition to provide a plurality of cushioned article-receiving cells, said inner cushioning bottom sections engaging said outer bottom walls adjacent the outer edges thereof and being held in spaced relationship therewith along the inner edges of the longitudinal partition; said inner cushioning bottom sections, outer bottom walls and lower section of the longitudinal partition forming a relatively rigid, truss-like support of substantially triangular shape for firmly supporting said inner cushioning bottom sections and longitudinal partition, with a smooth outer bottom surface for said carton.

7. A cellular carton comprising a blank of sheet material cut, scored and folded to form front and rear side walls, a double thickness central longitudinal partition having upper and lower sections, a cover hinged to said rear wall, a pair of outer bottom walls hingedly connected to said side walls along the lower edges thereof and extending inwardly into proximity with each other, a pair of longitudinally extending members hingedly connected to the respective outer bottom walls along the inner edges thereof and extending upwardly in juxtaposed relation with each other for forming the lower section of said longitudinal partition, a pair of inner bottom cushioning sections having lower plies hingedly connected to said upwardly extending members along the upper edges thereof and extending downwardly and outwardly into proximity with the junction between said side walls and

the respective outer bottom walls, said inner bottom sections having upper plies connected to the respective lower plies along the outer edges thereof and extending upwardly and inwardly towards the center of the carton in overlying relation with said respective lower plies, a second pair of upwardly extending longitudinal partition members hingedly connected to the respective upper plies of the inner cushioning bottom sections adjacent the upper edges thereof for forming the upper section of said longitudinal partition, said second pair of partition members being hingedly connected to each other along the upper edges thereof, and a top wall hinged to and connected with said front and rear walls and having therein a series of transverse partitions hingedly connected thereto and folded downwardly therefrom between said side walls and on opposite sides of said longitudinal partition to provide a plurality of cushioned article-receiving cells, said transverse partitions having their upper edges located in supporting proximity to said cover when the

partitions are in said down folded position, said inner cushioning bottom sections engaging said outer bottom walls adjacent the outer edges thereof and being held in spaced relationship therewith along the inner edges thereof by the lower section of the longitudinal partition; said inner cushioning bottom sections, outer bottom walls and lower section of the longitudinal partition forming a relatively rigid, truss-like support of substantially triangular shape for firmly supporting said inner cushioning bottom sections and longitudinal partition, with a smooth outer bottom surface for said carton.
